UNITED STATES PATENT OFFICE.

RICHARD SMITH, OF SHERBROOKE, QUEBEC, CANADA, ASSIGNOR OF ONE-HALF TO GEORGE W. RUSSELL, OF LAWRENCE, MASSACHUSETTS.

PAPER-GAGE.

SPECIFICATION forming part of Letters Patent No. 242,067, dated May 24, 1881.

Application filed October 13, 1880. (No model.)

To all whom it may concern:

Be it known that I, RICHARD SMITH, of Sherbrooke, in the county of Sherbrooke and Province of Quebec, Canada, have invented 5 certain new and useful Improvements in Paper-Gages, which improvements are fully set forth in the following specification, reference being had to the accompanying drawings.

The object of my invention is to provide an 10 instrument for readily ascertaining the thickness of paper and similar materials by means of the combination of a series of pivoted levers, links, and toothed wheels with a pair of receiving-jaws and indicator with supplementary 15 pointer.

Figure 1 is a front elevation of the instrument, showing part of the cover removed; and Fig. 2 is an end elevation of the same.

F is the frame or body of the instrument, 20 having a removable cover, C.

J' is an adjustable jaw, adjustable by means of the set-screw s', and held in its proper position in the groove q of the frame F by means of the tightening-screw s².

The spindle S, carrying the registering-jaw 25 J², is guided by the lugs l' l, forming part of the frame F, and is raised by means of the pivoted handle H, for the purpose of introducing the material to be measured between the jaws J' J², the spring G' serving to bring the registering-jaw to its proper position when pressure is removed from the handle.

p' p² p³ p⁴ p⁵ p⁶ are knife-edged pivots, of which p' is attached to the registering-jaw J², p² and p⁴ to the lever L', p³ and p⁵ to the frame F, and p⁶ to the lever L². The link K' communicates the motion of the registering-jaw J² to the lever L', having its fulcrum at p³, which,

in its turn, communicates the motion to an increased extent, by means of the link K², to the lever L², having its fulcrum at p⁵. The lever L², by means of the link K³, communicates the movement to a still greater extent to the lever L³, which, together with the quadrant Q, is attached to the spindle N'. The pinion P being 45 attached to the spindle N², to which is also attached the pointer R', and being in gear with the quadrant Q, thus causes the slightest variation in the position of the registering-jaw J², to be shown by the greatly-increased movement of the pointer R' around the dial D. 50

The case A, inclosing the dial D, is provided with a supplementary pointer, R², and is so attached to the frame F as to be revoluble about the dial, by which means the supplementary 55 pointer R² may be placed at any desired point of the graduated scale for purposes of comparison.

The spring G² is for the purpose of assisting the spring G' in bringing the respective parts 60 to their normal position.

I claim as my invention—

The combination, in a paper-gage, of the adjustable jaw J', the movable jaw J², controlled by the spring G', and connected at its inner 65 end with levers L' L² and quadrant-rack Q by links K', K², and K³, the pinion-wheel P, having on its spindle the index-pointer R', the dial-plate D, and case A, with its supplementary pointer R², all constructed substantially as and 70 for the purpose described.

RICHARD SMITH.
